UNITED STATES PATENT OFFICE.

JOHN E. HOFFMAN, OF CASPER, WYOMING.

WRECKING TOOL.

Application filed September 22, 1926. Serial No. 136,998.

This invention relates to a wrecking bar or tool of the character designed for use in salvaging lumber, dismantling framework and the like.

5 It is aimed to provide a novel construction possessing the details and advantages which will be specifically pointed out or appear in the description following taken in connection with accompanying drawings illustrating an operative embodiment.

In said drawings:—

Figure 1 is a view in perspective illustrating the tool as in use;

Figure 2 is a perspective view of the tool, 15 and

Figure 3 is a perspective view of the tool with the parts thereof disassembled to disclose details.

In carrying out the invention, an operating 20 pry or lever is shown at 10 having an integral cam portion as at 11 in which a disk 12 is loosely disposed for rotation. Said disk 12 has an eccentric hole 13, therein through which a rivet or bolt 14, loosely 25 passes, which bolt connects links 15 disposed at opposite sides of the lever 10. The forward ends of said links 15 are disposed in advance of the cam 11 and enter notches 16 of a shoe 17, in the form of a plate, and to 30 which shoe such ends are pivotally connected as by a pin or bolt as at 18.

At the forward end of the lever 10, it has a transverse cross head or abutment bar at 19, formed on a diagonal extension 20 of 35 the cam 11. Said bar 19 extends laterally beyond the plane of the corresponding sides of the shoe 17 for the purpose hereinafter stated.

In operation, the device may be used in 40 house wrecking, dismantling frameworks or the like and for instance to remove clapboarding as at 21 from scantling as at 22. The lever is manipulated so that the cross

head or bar 19 will engage against the scantling 22 on the edge to which the clapboard 45 21 is secured and the shoe 17 against the abutting face of the clapboard 21. With the parts in the positions stated the lever is rocked so that the cam action of the parts will serve to pry the clapboarding 21 loose 50 from the scantling 22. It will be understood that by using this tool for dismantling buildings the timbers will not be split or defaced but will be saved for reuse, and further that the device will save time in wrecking buildings. 55

Changes may be resorted to provided they fall within the spirit and scope of the invention.

I claim as my invention:—

1. A tool of the class described comprising a lever adapted for abutment against a part of the work, a shoe adapted for abutment against another part of the work, a disk journaled on the lever, means connecting the 65 shoe to the disk eccentrically of the latter.

2. A tool of the class described comprising a lever adapted for abutment against a part of the work, a shoe adapted for abutment against another part of the work, a 70 disk journaled on the lever, means connecting the shoe to the disk eccentrically of the latter comprising an arm pivotally connected to the shoe.

3. A tool of the class described comprising 75 a lever having a cam portion, a disk journaled in said portion, links at opposite sides of the disk pivotally connected thereto and eccentrically thereof, a shoe pivotally connected to the links, and a bar at the forward end of the lever disposed transversely thereof for engagement with the work in opposition to the shoe.

In testimony whereof I affix my signature.

JOHN E. HOFFMAN.
